DRAPERY TRAVERSE ROD OR SIMILAR ARTICLE

Annette E. Fridolph, New York, N. Y.

Application June 13, 1955, Serial No. 36,474

Term of patent 14 years

(Cl. D21—1)

FIG.1.

FIG.2.

Fig. 1 is a front elevational view of a drapery traverse rod or similar article, showing my new design; and
Fig. 2 is an end elevational view thereof.

I claim:

The ornamental design for a drapery traverse rod or similar article, as shown.
